D10-4

GR

No 13,171

EX

No 13,171.

UNITED STATES PATENT OFFICE.

FRANK H. HOTCHKISS, OF BIRMINGHAM, CONNECTICUT.

DESIGN FOR A CLOCK-CASE.

SPECIFICATION forming part of Design No. 13,171, dated August 8, 1882.

Application filed April 14, 1882. Term of patent 3½ years.

To all whom it may concern:

Be it known that I, FRANK H. HOTCHKISS, a citizen of the United States, residing at Birmingham, in the county of New Haven and State of Connecticut, have originated and invented a new and useful Design in Clocks; and I do hereby declare that the following is a full, clear, and exact description thereof, reference being had to the accompanying photographs, forming a part of this specification.

This design for a clock and case consists essentially, as shown in the accompanying photograph, in forming the same in the general shape or configuration of a castle.

In the photograph herewith, A represents the outer walls of the castle, which is shown as partly overgrown with ivy, B.

C represents the main door or gate way leading into the interior of the castle, said gate way having on either side the pillars b; and D is the clock-face, which is secured within the case so that said clock-face shall be immediately beneath the arch of said door or gate way.

E represents the interior, within which the clock-works are located.

F represents the pendulum of the clock.

G represents the steps leading to the door or gate way C.

H represents the main tower of the castle, 30 within or to the outer face of which is inserted or attached a thermometer, I.

J J represent the turrets.

K represents the ramparts or battlements, and L represents abutments.

M represents a small tower, having a door or gate way, N, and a window, O. The cap a of the tower M is hinged, so that it may be raised, as shown, and it is designed that this tower shall be used as a receptacle for matches 40 or other desired articles.

P P represent the loop-holes or windows usually formed in the side walls of the tower.

What I claim is—

A design for a clock, consisting of the representation of a castle, substantially as shown and described.

In testimony that I claim the foregoing as my own invention I affix my signature in presence of two witnesses.

FRANK H. HOTCHKISS.

Witnesses:

HENRY A. SMITH,
WM. W. SMITH.